ATTORNEYS

UNITED STATES PATENT OFFICE.

CONNY CLYDE RICKER, OF PADUCAH, KENTUCKY.

RAIL-ANCHOR TIE PLATE.

Application filed March 22, 1926. Serial No. 96,576.

My invention relates to improvements in rail anchor tie plates, and it consists in the combinations, constructions, and arrangements herein described and claimed.

5 An object of my invention is to provide a device of the type described which will prevent movement of a rail in any direction.

A further object of my invention is to provide a device of the type described which 10 can readily be applied to a rail and secured to a railway tie by any system of spiking.

Other objects and advantages will appear in the following specification, and the novel 15 features of the invention will be particularly pointed out in the appended claim.

My invention is illustrated in the accompanying drawings, forming part of this application, in which—

Figure 1 is a side elevation of the device, 20 Figure 2 is a plan view of the railway track, showing the device applied to the rails,

Figure 3 is a modified form of the device,

Figure 4 is a modified form of the device, 25 and

Figure 5 is a plan view of the modification shown in Figure 4, as applied to a railway track.

In carrying out my invention I provide a 30 rectangular support 1 having apertures 2 and 3 formed therethrough. The upper surface of the support is provided with integral abutting flanges 4. A pair of resilient lugs 5 are integral with the support 1 and 35 are of the shape shown in Figure 1.

From the foregoing description of the 40 various parts of the device, the operation thereof may be readily understood. To apply the device to a rail indicated at A, the rail is raised a sufficient distance to permit the support to be pushed underneath the rail until the lugs 5 strike the portion B of the rail base. Then, by striking either 45 the resilient lugs or the end of the support

adjacent the lugs, the support is driven further beneath the rail base to such an extent 45 that the abutting flanges on the opposite side of the support will clear the opposite side of the rail base and come up on the side thereof. Spikes are then placed in 50 either one or all of the apertures 2 and 3, and the support rigidly secured to a tie. By applying a plurality of the devices to each rail, as shown in Figure 2, the rail is positively held against movement in any direction. The device is so applied to the rails that the resilient lugs 5 will be upon the inside. In this manner, the rails are more firmly held upon the inside, the reason for 55 this being that the force upon a rail is in an 60 outward direction.

The main object of the device is to prevent longitudinal movement of the rail, but the device is so constructed as to prevent 65 the rail from moving in any direction.

In Figure 3, I have shown a modified form 70 of the device comprising a rectangular support 6 having apertures 7 and 8 formed therethrough. The upper surface of the support 6 is provided with integral abutting flanges 9 and an elongated resilient plate 10.

In Figure 4, I have shown another modified form of the device which is similar in construction to the device shown in Figure 1, with the exception of the resilient lugs. 75 The modified form shown in Figure 4 has but one resilient lug 11 which is disposed near the center of the support 12. In Figure 5, I have shown this device applied to rails.

I claim:

The combination with a railway tie, of a rail anchor tie plate having four apertures formed therethrough for permitting said plate to be secured to said railway tie, abutting flanges in alignment with two of said apertures, and resilient lugs bent upwardly and backwardly for rigidly holding a rail.

CONNY CLYDE RICKER.
